Primary Examiner—Melody N. Brown*Attorney, Agent, or Firm*—Howell & Haferkamp, L.C.**[57] CLAIM**

The ornamental design for a truck bed tool box with a single access door, as shown and described.

DESCRIPTION

FIG. 1 is a perspective view of a truck bed tool box with a single access door showing my new design;
 FIG. 2 is a top plan view thereof;
 FIG. 3 is a front elevation view thereof;
 FIG. 4 is a rear elevation view thereof;
 FIG. 5 is a bottom plan view thereof; and,
 FIG. 6 is a left side elevation view thereof, the right side elevation view being a mirror image thereof.
